[57] CLAIM

The ornamental design for a projection lens support enclosure for attachment to a television receiver, as shown and described.

DESCRIPTION

FIG. 1 is a top plan view of a projection lens support enclosure for attachment to a television receiver showing my new design;

FIG. 2 is a right side elevational view, the left side being substantially a mirror image thereof;

FIG. 3 is a front elevational view;

FIG. 4 is a rear elevational view; and

FIG. 5 is a bottom plan view.
